UNITED STATES PATENT OFFICE

1,971,049

HINGED PIN LOCK

Stephen Pelle, New York, N. Y.

Application June 22, 1932, Serial No. 618,612

4 Claims. (Cl. 70—53)

This invention relates to locks and is an improvement on my invention for locks for which an application for a patent of the United States has been filed, No. 601,433, on March 26, 1932, being based on the same basic principles but being different therefrom in the construction, combination and operation of the parts.

The main object of the present invention is to provide a device of the character mentioned, which will be efficient, inexpensive, which will provide a great number of combinations in the operating elements by easily changeable simple means, which will be safe in its locking action, and the locking means whereof will be adapted to be permanently disengaged and put into an inoperative position, when so desired, and returned to locking position by a simple, quick and easy method.

Other objects of this invention will be apparent as the specification of the same proceeds.

In the drawings, forming a part of this specification and accompanying the same:

Fig. 1 is a plan view, partly in section, of a lock embodying my invention.

Fig. 2 is a sectional front elevation taken on the line 2—2 of Fig. 1.

Fig. 3 is a fragmentary rear view as seen from the direction of the arrow 3 of Fig. 1.

Fig. 4 is a vertical sectional elevation taken on the line 4—4 of Fig. 1.

Fig. 5 is a plan view of one of the tumblers of a lock embodying my invention.

Fig. 6 is a side elevation of the tumbler of Fig. 5.

Figs. 7 and 8 are semi-diagrammatical simplified plan views of other tumblers of my lock.

Fig. 9 is a partly sectional plan view of the tumblers and their casing with the rear portion of the casing removed, showing a return spring for the tumblers.

Fig. 10 is a front elevation on a reduced scale showing the parts of the lock in the open or unlocked position.

Figs. 11 to 15 are partial detail views of forms of key for my lock, and corresponding parts of the lock, respectively.

Referring to the drawings by characters of reference the numeral 10 indicates an object to which my lock is applied, in this case a door, and its frame. It is not intended to limit the use of my lock to doors mounted on single hinges, as it may also be applied to doors which are adapted to swing to either side of their supporting frame, or to double doors. As constructed the lock is also efficiently applied to cabinets, closets, boxes,

and may be modified to be applied to drawers and other articles.

The lock proper is housed in a circular casing 15 formed with two circular indentations 16—16, the inner surfaces 17—17 forming a "race" or support which rotatably holds the tumblers 20, 21, and 22 (Figs. 3 to 8) later more fully described, in alignment. The inner surfaces 18 of the casing provide clearance for projections 30 of the tumblers. At the uppermost portion of the casing 15, there are provided three openings 19 beyond which the tumblers pass in a clockwise direction.

The tumblers 20, 21 and 22 are generally similar and are formed with hubs 23, supporting discs 24. Said discs are provided on their circumferences with a plurality of short spokes 25 outwardly offset from the disc proper, and are further staggered so that the spokes on one side of the disc may be said to be advanced or staggered with regard to the spokes offset to the other side of the disc, the simplest method to reach this relation being to suitably bend said spokes, as shown.

The spokes 25 carry a circular rim 26 serrated on both edges as at 27, whereby the serrations of the rim cooperate with the spokes 25, offset or staggered to support the rim in a great number of positions relative to one position of the hub. Each rim 26 is further provided with two short outwardly offset arms 28—28 at its free ends over which a shallow metal cap 30 may be pressed. The hubs 23 exceed the thickness of the circular rims 26 whereby when the tumblers are in place in the case 15 the innermost and outermost hubs 23 bear respectively against the back and front of the casing 15 and the hub 23 of the central tumbler bears against the hubs adjacent to it. (See Fig. 4.)

The hub 23 of the innermost tumbler 20 is provided with a tubular extension 31 integral therewith, while the hubs of the tumblers next adjacent are provided with similar but wider extensions 32 and 33, whereby the said extensions telescope within one another and differ in length by the thickness of any hub so that their ends where they project beyond the door, are equal. The largest hub 33 revolves freely in a keyhole 35 also tubular in form, which projects slightly beyond the ends of the extensions 31, 32, and 33, and is fastened to the casing 15 and the door 10 by screws or other means well-known in the art. The ends of the tubular extensions 31, 32 and 33 of the tumbler hubs are further provided with pins 31', 32' and 33' respectively, projecting out-

wardly therefrom to cooperate with similar pins, mounted on a key, later described.

A stop pin 36 mounted on the inner side of the casing 15 engages the cap 30 of the innermost tumbler 20. A spiral spring 37, anchored at one end to the casing 15, as at 38, and at its other end to the hub 23, as at 39 maintains the cap 30, of said tumbler, in such engagement.

A pin 40 extending to the front of the disc 24 of the tumbler 20, engages the rearward extension of a pin 41 on the disc 24' of the tumbler 21, the forward extension of said pin similarly engaging another pin 42 extending rearwardly of the disc 24' of the tumbler 22. The above mentioned pins are equally spaced radially, whereby under the action of the spiral spring 37 the three tumblers are brought back to a convenient zero position, and so remain until the pins 31', 32' and 33' of the respective hub extensions are engaged by a key to unlock the door. A bolt 50 of rectangular cross-section is slidably mounted in a casing 51. The upper surface of said casing is provided with a slot 52 engaging a pin 53 mounted on the bolt 50 and thereby limiting its reciprocal movement. The door frame proper 10' is provided with a conventional form of lock plate 54 to engage the bolt 50. A compression spring 55 loosely held in place by a stud 56 of the casing 51 exerts its pressure on a downwardly extending projection 57 of the bolt 50. Said extension has a vertical slot 58 cooperative with a pin 59 extending through it, and carried by a short lever 60 operated from either side of the door by the handles 61-61. A reduced portion 65 of the bolt 50 extends inwardly and carries pivotally mounted thereon, as at 66, a series of metal fingers 67 one for each tumbler, of rectangular cross section adapted to engage in the locked position with their reduced or stepped ends 68, the inner edges 40 of the openings 19 of the casing 15.

A leaf spring 69, is mounted on the top of the extension 65 by screws or other convenient means and with its widened end 70 exerts a downward pressure on the fingers 67 tending to keep said fingers in engagement with the casing 15.

A plate 71, arcuate in form, and approximating in width that of the casing 15 is slidably mounted to the left of the openings 19 of said casing, and is provided with a lever 71' projecting inwardly 50 of the door, whereby the plate is adapted to be moved in a counter clockwise movement to unlock the door from the inside, as will be more fully described hereinafter.

In Figs. 11 and 12, one form of key is illustrated 55 while a modification of this form is shown in Fig. 13.

A series of nesting cups 75, 76, and 77 having central aligning holes 78 are adjustably fastened to a tubular shank 79 by a nut and bolt, as at 80. 60 These cups are of lengths differing by the thickness of their bases whereby their outer ends are in the same plane when secured together, and are provided with pins 75', 76', 77' which cooperate with the pins 31', 32', 33' on the tumbler 65 hubs to unlock the door.

It is obvious that by the construction of the tumblers 20, 21 and 22 previously described many positions of the caps 30 with respect to the pins 31', 32', 33' are readily obtained, and the relative 70 positions thus obtained between the caps and the pins provide a large number of different combinations. A similar number of corresponding positions are possible with respect to the adjustments of the pins 76', 76' and 77' of the key.

75 It is also obvious that these many changes in

the combinations of the lock elements and the corresponding unlocking positions of the parts of the key may be easily and quickly made with the construction above described, whereby a simple and inexpensive lock of wide application is provided.

80 The key shown in Fig. 13 differs from the one previously described by the addition of a circular shield extending beyond the pins 75', 76' and 77' and which may be integral with the outer cup as shown at 81, thus protecting the clothing of the person carrying the key.

85 A slightly different form of key is shown in Fig. 14 where the lengths of the cups 85, 86, and 87 vary so that the ends thereof are staggered. The outer cup 87 is provided with a shield similar in construction and purpose to that of the key of Fig. 13. The ends of the cups 85, 86, and 87 carry pins 85', 86' and 87' similar to those previously described, to engage pins 31', 32', 33', which in this case, as shown in Fig. 15, are carried by extensions of the tumbler hubs, said extensions being of, co-operating lengths to match the staggered ends of the key last described.

90 The operation of my novel lock is as follows:

Assuming my lock just described to be in the closed position, as best shown in Fig. 2, its operation from the outside is the following: A key as illustrated in Figs. 11 to 13 is inserted in the key-hole and turned in a clockwise direction. The pins 75', 76' and 77' of the key will engage in order the corresponding tumbler hub extension pins 31', 32', 33', whereby the tumblers 20, 21 and 22 will likewise turn in clockwise direction. As will be understood, the relative arrangement of said pins and the caps 30 on their tumblers to said respective tumbler pins is such that continued movement will cause the caps 30 of the tumblers to simultaneously engage the corresponding fingers 67 and lift them out of engagement with the rearward edges of the openings 19 of the casing 15 against the compression of the leaf spring 69, thereby releasing the bolt 50.

105 The parts now take the position shown by full lines in Fig. 10. The bolt 50 is withdrawn by the action of the spring 55 and the fingers 67 slide inwardly on the top edge of the casing 15. At the same time, both knobs 61 are turned slightly in a clockwise direction through the action of the pin 59 in the slot 58 of the bolt extension 57.

110 Upon withdrawal of the key from the keyhole the tumblers 20, 21, and 22 return to the zero position against the stop 36 through the action of the spiral spring 37 and the interlocking pins 40, 41 and 42, as shown in Fig. 2, but the bolt remains withdrawn or in open position. The lock may now be closed from either side of the door by turning the respective knob 61 in a counter clockwise direction, whereby the bolt 50 is moved outwardly under the action of the lever 60, pin 59 115 and slot 58 of the bolt extension 57, against the compression of the spring 55, until the fingers 67 snap downwards into their respective openings 19 in the casing 15 and the stepped ends 68 of the fingers come to rest on the rearward edges of said 120 openings.

125 To unlock the door from the inside I provide an arcuate plate 71 slidably mounted on the casing 15, and provided with an inward extension terminating in a lever 71', accessible from the inside of the door, as shown in Fig. 3. A movement to the left of said lever and plate causes the plate 71 to simultaneously disengage the fingers 67 from the rearward edge of the 130

casing 15 whereby the bolt is withdrawn by the action of the spring 55 as previously explained. To maintain the door in unlocked position the lever 71' may be left in the position just described where it will be frictionally held by the fingers 67 and the spring 69.

To lock the door from either side thereof after its permanent unlocked position has been obtained, plate 71 must be returned into its idle 10 right hand position, then knob 61 turned so as to move bolt 50 into locking position whereupon fingers 67 snap back into engagement with the edges of openings 19.

To change the combination of the lock, the 15 rims of tumblers 20, 21 and 22 will be released and spoke ends 25—25 moved into new positions in relation to the parts of the serrations 27 which they engage.

I want to remark that changes and variations 20 may be resorted to in the construction parts and arrangement and combination thereof in my device and I want to reserve my right to all such changes which are within the spirit of this specification and the scope of the appended 25 claims.

What I claim as new, is:

1. In a lock having a locking bolt slidable 30 therein and spring means to normally urge said locking bolt into an open position, a circular stationary housing; a plurality of circular tumblers being rotatable in said housing, said housing also having an opening for every tumbler at a portion in its outer circumferential wall; a radial projection on every tumbler; a hinged finger on said bolt for every tumbler bridging said opening and engaging a portion of said casing and thereby preventing the opening of said bolt; spring means to normally press said fingers into engagement with 35 said casing, said projections being adapted to 40 said casing, said projections being adapted to

release a respective finger when passing through said opening underneath said finger.

2. In a lock as set forth in claim 1, means on 80 said tumblers whereby the same may be rotated and said projections caused to pass through said openings simultaneously.

3. In a lock as set forth in claim 1, means on 85 said tumblers whereby the same may be rotated and said projections caused to pass through said openings simultaneously; a pin secured to said casing adapted to be engaged by the projection on the lowermost tumbler; spring means to cause said lowermost tumbler to engage said pin, and co-operating pins on said tumblers so that the rotation of any one will carry the adjacent 90 tumbler so that normally all the tumblers will be pressed against said pin on the casing and their projections will not be in circumferentially registering relation.

4. In a lock having a locking bolt slidable 95 therein and spring means to normally urge said locking bolt into an open position, a circular stationary housing; a plurality of circular tumblers being rotatable in said housing, said housing also having an opening for every tumbler at a portion in its outer circumferential wall; a radial projection on every tumbler; a hinged finger on 100 said bolt for every tumbler bridging said opening and engaging a portion of said casing and thereby preventing the opening of said bolt; spring means to normally press said fingers into engagement with said casing, said projections being adapted to release a respective finger when passing through said opening underneath said finger; an arcuate member slidable on the outside of said circular casing adapted to bridge 105 said openings and raise said fingers out of their locking positions, and means projecting to the outside of the lock to operate said arcuate 110 member.
